UNITED STATES PATENT OFFICE.

WILLIAM E. NAGEBORN, OF DETROIT, MICHIGAN, ASSIGNOR TO GRAY MOTOR COMPANY, OF DETROIT, MICHIGAN, A CORPORATION OF MICHIGAN.

GAS-ENGINE.

1,010,785.

Specification of Letters Patent.

Patented Dec. 5, 1911.

Application filed November 13, 1908. Serial No. 462,383.

To all whom it may concern:

Be it known that I, WILLIAM E. NAGEBORN, a citizen of the United States, residing at Detroit, county of Wayne, State of Michigan, have invented a certain new and useful Improvement in Gas-Engines, and declare the following to be a full, clear, and exact description of the same, such as will enable others skilled in the art to which it pertains to make and use the same, reference being had to the accompanying drawings, which form a part of this specification.

My invention relates to gas engines, and consists in the improvements hereinafter described and pointed out in the claims.

In the drawings: Figure 1, is a side elevation of a gas engine embodying my invention. Fig. 2, is a vertical section of the same, omitting the reservoirs 7 and 8 and the two pipes leading therefrom, the section being taken in the plane indicated by the line *d*, *d*, Fig. 5. Fig. 3, is a section on the line *c*, *c* Fig. 2. Fig. 4, is a section on the line *b*, *b* Fig. 2, except that, the piston is taken as in a lower position than that indicated in Fig. 2, so that the ports, 24, through the wall of said piston, shall be in the plane of section. Fig. 5, is a section on the line *a*, *a* Fig. 2. Fig. 6, is an elevation of the piston detached from the engine. Fig. 7, is a detailed section on the line *e*, *e*, Fig. 2.

2 is the cylinder of a two-cycle engine. 3 is the crank case in which a charge of air is compressed by the descending piston. 4 is the exhaust pipe, and 5 the intake pipe.

6 is a detachable casing which forms a part of the communicating passage between the crank case and the cylinder above the piston.

7 is a reservoir for containing the liquid fuel for the engine. 8 is an auxiliary reservoir which may contain a lighter fluid for starting the engine.

9 is a connecting pipe leading from the reservoir 7 to the interior of the casing 6.

10 is a check valve in the pipe 9, opening away from the reservoir 7.

11 is a needle valve for adjusting the size of the passage from the pipe 9, to the interior of the casing 6.

12 is a hollow piston adapted to reciprocate in the cylinder 2.

13 is the main shaft of the engine.

14 is the crank.

15 is the connecting rod pivoted to the piston 12 at 16.

17 is the deflector at the top of the piston.

18 indicates that edge of the piston which passes over a port to open communication between the crank case, and the cylinder 2 above the piston 12.

19 is the exhaust port.

20 is a port which is uncovered by the passage of the edge 18 of the piston 12, as hereinafter described.

21 is a port through the wall of the cylinder 2, which communicates with the crank case 3, through apertures 23, in the piston wall when the port 20 is open to the combustion chamber, as hereinafter described.

22 is an intake port through which air is admitted to the crank case 3 through the wall of the cylinder 2, when said port is opened by the passage of the lower edge of the piston 12.

23 indicates apertures formed through the wall of the hollow piston 12, near the upper end of said piston.

24 indicates small apertures formed through the wall of the hollow piston 12, about midway between the upper and lower ends of said piston.

24^a are oil grooves in the outer wall of the piston 12. The aperture 24 may communicate with a groove 24^a.

25 is the intake passage through which gasoline is supplied to the interior of the casing 6.

26 is a foraminous diaphragm or partition in the casing 6 dividing it into a lower chamber 29, and an upper chamber 30.

27 indicate small apertures through the partition 26.

28 is a cavity at the center of the partition 26, leading in from the upper surface of said partition and communicating with the intake passage 25 for the liquid fuel.

31 (Figs. 2 and 7) is a throttle valve in the casing 6, adapted to be turned to adjust the passage to the port 20, by the handle 32.

There are ribs, 21^a, extending vertically across the port 21; 22^a, are similar ribs across the port 22.

The operation of the above described device is as follows: As the piston 12 commences to rise it produces a partial vacuum 10 in the crank case 3; when said piston is approaching the position shown in Fig. 2, the small apertures 24 through the wall of said piston commence to register with the port 20, thus producing a partial vacuum in the 15 chamber 30, and causing the fluid to be driven from the reservoir 7 through the pipe 9, and passage 25 into the cavity 28, and, perhaps, upon the upper surface of the partition 26. The valve 10 prevents the 20 return of the fluid when the pressure is restored in the chamber 30. As the piston 12 continues to rise its lower edge passes over the intake port 22, admitting air to the crank chamber 3 and destroying the 25 vacuum in said chamber so that there is no longer a suction tending to draw the liquid fuel into the casing 6, as above described. Upon the downward stroke of the piston 12, air is compressed in the crank case 3, and 30 when the ports 23 register with the port 20 the compressed and heated air is forced into the chamber 30, to assist in vaporizing the liquid fuel on the diaphragm 26 or in the cavity 28. During said downward 35 stroke of the piston the apertures 24 are kept covered by the walls of the cylinder 2, or the ribs 21^a and 22^a, Figs. 3 and 4, as indicated more particularly in the last named figure. When the apertures 23 register 40 with the port 21, the edge 18 at the upper end of the piston 2 passes below the upper edge of the port 20, to open said port and the air compressed in the crank case is driven through the port 21, the casing 6, the 45 foraminous diaphragm 26, and vaporizes and mixes with the liquid fuel and passes through the port 20, to the upper part of the cylinder 2 and displaces the burned products of combustion from previous stroke 50 through the exhaust port 19, as in the well understood process of the two-cycle engine. The change in pressure of the air in the

crank case will act through the apertures 24 to distribute the oil in the groove 24^a, should these apertures communicate with such a 55 groove.

What I claim is:

1. In a two-cycle gas engine, the combination of a cylinder, a piston therein, said cylinder being provided with a compression space below said piston and a combustion chamber above said piston, a passageway adapted to form a communication between said compression space and combustion chamber, a port 20 at the delivery end of 60 said passageway, a port 21 at the intake end of said passageway, an aperture 23 in the piston adapted to register first with the port 20 and then the port 21 on the stroke of said piston, producing a compression in 70 said compression space, a passage for liquid fuel opening into said passageway, the piston being provided with an aperture 24 adapted to register with the port 20 at a point intermediate in the up-stroke of said piston. 75

2. In a two-cycle gas engine, the combination of a cylinder, a piston therein, said cylinder being provided with a compression space below said piston and a combustion chamber above said piston, a passageway 80 adapted to form a communication between said compression space and combustion chamber, a port 20 at the delivery end of said passageway, a port 21 at the intake end of said passageway, an aperture 23 in the 85 piston adapted to register with the port 20, and then the port 21 on the stroke of said piston, producing a compression in said compression space, a passage for liquid fuel opening into said passageway, an aperture 90 24 in the piston adapted to register with the port 20 near the end of the compression stroke of said piston and ribs 21^a across the inlet port 21 to said passageway adapted to cover the ports 24 during the stroke of the 95 piston, substantially as and for the purpose described.

In testimony whereof, I sign this specification in the presence of two witnesses.

WILLIAM E. NAGEBORN.

Witnesses:

ALECIA TOWNSEND,
ELLIOTT J. STODDARD.
